UNITED STATES PATENT OFFICE.

CHARLES F. MOSMAN, OF MERIDEN, CONNECTICUT, ASSIGNOR TO C. ROGERS & BRO., OF SAME PLACE.

DESIGN FOR A DRAWER-PULL.

SPECIFICATION forming part of Design No. 12,500, dated September 27, 1881.

Application filed August 22, 1881. Term of patent 7 years.

To all whom it may concern:

Be it known that I, CHARLES F. MOSMAN, of Meriden, in the county of New Haven and State of Connecticut, have invented a new Design for Drawer-Pulls; and I do hereby declare the following, when taken in connection with the accompanying drawing and the letters of reference marked thereon, to be a full, clear, and exact description of the same, and which said drawing constitutes part of this specification, and represents a front view.

This invention relates to a design for drawer-pull, particularly to that class which have a pull hinged to a socket or base, so as to drop into a vertical position in front of the drawer; and the invention consists in a horseshoe-shaped base, with connections or bars from the shoe inward to support the socket, as more fully hereinafter described.

A represents the base, in the shape of a horseshoe. At the center is the socket B. From each side of the shoe a bar, C, extends inward to the socket, and from the toe of the shoe a like bar, D, extends downward to the socket, and, apparently crossing the bar C, terminates in a tip, E, below, the socket resting at the center where the bars cross. To the socket the tip F is hinged.

I claim—

The herein-described design for drawer-pull, consisting of the horseshoe-shaped base, central socket, and bars extending from the sides and toe of the shoe inward to the socket, as shown in the accompanying illustration.

C. F. MOSMAN.
